CAN OPENER

Joseph W. Gibney, Port Chester, N. Y., assignor of
one-half to Lawrence R. McWeeney, Rye,
N. Y.

Application October 28, 1940, Serial No. 363,163

6 Claims. (Cl. 30—16)

This invention relates to can openers and more particularly to a device for opening the top of a can and forming a pouring spout.

Can openers have heretofore been devised for forming a pouring spout in the top of a can but such devices have been open to one of several objections. In some instances the device is so constructed that it must engage the can top at diametrically opposite points. This either necessitates a separate opener for each diameter of can or requires the provision of adjusting means for a single device to permit it to be used with cans of different diameters.

Other forms of devices which have been proposed are formed of complicated constructions and do not provide sufficient leverage to permit a woman to open the can. In other devices a piercing member is provided which enters the top of the can and comes in contact with the contents of the can.

In the present invention I provide an opener that is capable of forming a pouring spout that can be used on any size can and does not require adjustment. The device is of simple construction and easy to operate. It provides ample leverage to permit its use by a woman.

An important feature of the present invention is the fact that no part of the opener enters the can and comes in contact with the contents. The device is therefore sanitary and possesses a decided advantage over those prior devices in which a piercing member enters the top of the can.

In the accompanying drawing I have shown one form of the invention. In this showing:

Fig. 1 is a side elevation of the opener in position on the top of a can;

Fig. 2 is a bottom plan view of the device;

Fig. 3 is a vertical, sectional view showing the can in opened position;

Fig. 4 is a horizontal, sectional view through the two operating members of the can opener with the can in opened position; and

Fig. 5 is a plan view of the opened can.

Referring to the drawing the reference numeral 1 designates a can of ordinary construction provided with a top 2. In the standard method of manufacturing cans of this character the top is originally of greater diameter than the can and its periphery is folded or crimped over the upper edge of the can as at 3 to secure the can top in position. The can opener forming the subject matter of the present invention is adapted to move a portion of the can wall outwardly and to shear the crimped portion 3 from

the body portion 2 of the can top to form an opening between the can top and the can as shown in Figs. 3 to 5 of the drawing.

The can opener consists essentially of two members, one of which engages the outside of the can beneath the can top and forms one of the shearing blades and the other of which engages the crimp or bead of the can top to perform the opening operation. The base member may consist of a pair of parallel arms 5 connected at one end by a web 6. The opposite end of the base member is provided with a can engaging member 7. As shown the can engaging member 7 is in slightly depending position and when the device is applied to the can it is adapted to engage the outer wall of the can just below the level of the can top 2. The edge 8 of the member which forms one of the shearing blades adjacent the wall of the can is concaved as shown and the curvature is formed on a radius smaller than that of the can so that when the adjacent can wall is forced out against this edge it will be deformed to form a pouring spout 9 as shown in Figs. 3, 4 and 5 of the drawing. The concave edge 8, instead of being formed in a single curve may be formed of a pair of separate curves providing a substantially straight central portion 10.

At each end of the curve portion, I provide a straight portion 10' forming a projection which engages the can wall just below the bead or crimp as shown in Figs. 1 and 3 and prevents the can opener from slipping or becoming displaced during the opening operation.

The movable member consists essentially of an arm 11 which is provided between the two walls 5 of the base member. As shown the inner end of this arm is secured within a member 12 which is substantially U-shaped in cross-section and which fits snugly between the walls 5 of the base member. The two members are pivoted together by a pivot pin 13 which passes through aligned openings in the walls 5 and 12 and which may be secured in position by any suitable means, such as cotter pins 14.

The bottom 15 of the U-shaped member 12 is provided with a front edge or blade generally similar in shape to the edge 8 of the member 7 and consisting of a pair of curved portions 16 connected by an oppositely curved portion 17. The overall arc of the curves 16 and 17 is upon a radius smaller than that of the can.

In operation the can opener is placed on the top of a can in the position shown in Fig. 1 of the drawing with the outer engaging member 7 below the surface of the can top and engaging

the outside wall of the can. The handle 11 is then swung on its pivot bringing the curved edge of the U-shaped member 12 against the inside of the bead or crimp of the can top as shown in Fig. 1. As the handle is swung further toward a horizontal position, engagement of the outer wall of the can by the ends of the curves 10 forms an abutment against which the wall of the can is curved by the further movement of the member 12 upon its pivot. As the member 12 swings in an arc above the depending member 7, it pushes the can wall outwardly between the two points where the can wall is engaged by the outer member and as this outward movement continues, the head 3 is sheared from the can top 2 and the spout 9 is formed. The opener assumes the position shown in Figs. 3 and 4 of the drawing producing a spout as shown in Figs. 3 to 5 of the drawing.

The operation is simple to perform and produces a spout without any portion of the can opener entering the can and coming in contact with the contents. The advantage of this is apparent as otherwise a can opener which has become soiled may contaminate the contents of the can. Furthermore as stated, the device may be used upon a can of any diameter without adjustment.

I claim:

1. A can opener comprising a base member having a portion adapted to engage the exterior wall of the can and forming a shearing blade, a second member pivoted to the base member, and means carried by the second member to engage the inner side of the crimped top of the can to force the can wall outwardly and shear the crimped top.

2. A can opener comprising a base member having a depending portion to engage the exterior wall of the can below the can top and forming a shearing blade, a second member pivoted to the base member and means carried by the second member to engage the inner side of the crimped top of the can and force the can wall outwardly against the depending portion of the base member and shear the crimped top of the can.

3. A can opener comprising a base member having a depending portion to engage the exterior wall of the can below the top, the engaging portion being provided with a concaved face con-

caved on a radius shorter than that of the can wall, a second member pivoted to the base member, and means carried by the second member to engage the inner side of the crimped top of the can to force the can wall outwardly against the concaved face of the exterior member and shear the crimped top.

4. A can opener comprising a base member having a depending portion to engage the exterior wall of the can below the can top, said depending portion having a concaved face curved on a radius shorter than that of the can wall, a second member pivoted to the base member and a shearing member carried by the second member and engaging the inner side of the crimped top of the can, the engagement of said member being adapted to force the can wall outwardly against the concaved face of the depending member and to shear the crimped top of the can to form a pouring spout.

5. A can opener comprising a base member adapted to rest on the top of the can, a depending engaging member carried thereby and engaging the exterior wall of the can below the can top, said depending member having a concaved face to engage the can wall at two spaced points, and a second member pivoted to the base member, the second member comprising a handle and a shearing member, the shearing member swinging in an arc over the depending engaging member and being adapted to engage the inner side of the crimped edge of the can top to move the adjacent portion of the can wall outwardly and to shear the crimped portion of the top.

6. A can opener comprising a base member adapted to rest on the top of the can, a depending, engaging member carried thereby and engaging the exterior wall of the can below the can top, said depending member having a concaved face and having a projection formed on each end of the concaved face, and a second member pivoted to the base member, the second member comprising a handle and a shearing member, the shearing member swinging in an arc over the depending engaging member and being adapted to engage the inner side of the crimped edge of the can top to move the adjacent portion of the can wall outwardly and to shear the crimped portion of the top.

JOSEPH W. GIBNEY.
